UNITED STATES PATENT OFFICE

ABRAHAM BERNARD DIBNER, OF BROOKLYN, NEW YORK

ELECTRICAL CLAMP CONNECTER

Application filed June 17, 1925. Serial No. 37,754.

My invention relates to improvements in clamp connectors for electrical installations.

Outdoor types of installations involving high voltages usually employ copper tubular buses and their shape is designed to provide maximum mechanical strength, high conductivity, and the least provision for corona losses. These copper tubular buses are round in section and are ordinarily manufactured in standard lengths. Modern installations require buses exceeding these standard lengths and providing a continuous path for the currents. In practice the buses are connected together end to end, and where conditions care for a curve, elbows are used instead of bending the tubing.

Therefore, it has been necessary to provide means whereby such lengths of tubing may be connected together end to end or at angles to each other. Various provisions have been made for this work varying in efficiency with the design. Among the difficulties encountered is the variation in dimensions for both the inside and outside diameter of the copper tubing. This condition is the result of the process of manufacture which cannot limit itself to any degree of accuracy. These variations in diameter make the connector for connecting separate pieces of tubing together of a nature which lends itself to adjustment. The means used to provide for such adjustment varies in the several designs of connectors in the market. Some manufacturers produce connectors requiring a shrink fitting, others soldering, but the most common form is that of bolting contacting parts together.

Copper tubing forming the buses of the outdoor installation is subject to the vibrations of weather and electro-mechanical shocks of an electrical installation. The vibrating strands tend to strain the members and to misalign the adjustments provided at the time of installation.

With the foregoing in mind, it is the purpose of the present invention to provide a clamp connector of this character which is designed to overcome the difficulties usually encountered in outdoor electrical installations and I accomplish this purpose by means of

the device illustratively exemplified in the accompanying drawings, in which,

Figure 1 is an elevational view of my improved straight line connector and Figure 2 is an end view of the same. Figure 3 is an elevational view of a curved connector and Figure 4 is an end view of the same.

Referring to the drawings, and particularly to Figures 1 and 2, 10 designates a single body portion having a through bore 11. The body 10 is split throughout its entire length and at opposite ends the cut 12 extends longitudinally of the body, then at their inner ends the cut projects transversely to a point at right angles to the end cuts 13 and thereafter extends longitudinally to complete the separation of the material on one side of the connector.

On each side of the end cuts, the body is provided with projecting ears 13 which receive bolts 14 disposed tangentially to the body 10 and which are relatively adjustable with respect to each other by means of nuts 15 arranged over the ends of the bolts. Adjacent the opposite ends of the central portion of the cut 12, the body is provided with two sets of ears 16 similar to the ears 13 except that they are disposed at substantially right angles to the latter ears. The ears 16 are also provided with bolts 17 and adjustable nuts 18, which, if adjusted with the nuts 15 will make the clamping action of the connector effective at every point about the periphery of the tube bus.

The embodiment of the invention shown in Figures 3 and 4 is identical with that shown in the preceding figures, except that the central portion is curved to conduct current at an angle.

It will be clear that the general nature of a connector of this character is that of a tubing to fit equally over each of the bus ends to be connected. The cross section of this tube is equal in electrical conductivity to that of the buses, and equal in mechanical strength to that of the buses. The bore 11 is machine finished and of a diameter equal to the outside diameter of the tubular buses. The nuts 15 and 18 are tightened and the grip of the connector about the bus is effected to

engage the contacting surfaces so as to provide an efficient path for the travel of the electrical currents from bus through connector to bus. The connector is constructed to grip each bus with the clamping force of the two bolts 14 and 17, which are spaced at an angle about the periphery of the connector. This provides a clamping force at a multiple number of points about the contacting surfaces and so insures contact.

10 The connector is installed by sliding the latter equally over each end of the buses to be connected until these buses abut each other at the center of the connector. The nuts are 15 then tightened and the installation is complete.

10 The advantages of the improved connector are: first, the body 10 comprises a single element without having attachable parts; second, the placing of the bolts at an angle to each other minimizes differences in diameters 20 of the inner surface of the connector and outer surface of the tubing by the gripping force being disposed at angles to each other. Therefore, deformations in the tubing due to 25 the process of manufacture and handling are of slight importance by the efficient clamping and contacting features; and third, the mechanical stresses to which buses are subjected 30 will usually be in a fixed plane depending upon the method of support; therefore, the disruptive forces in their tendency to loosen the gripping bolts might be successful upon one set thereof, but the other set being at 35 right angles to the plane of movement will succeed in retaining their grip and keeping the surfaces in contact.

What I claim is:

1. A clamp connector comprising a tubular 40 body, split from end to end, the cut forming the split having portions extending longitudinally inward from each end of the tubular body, and portions extending transversely around the tubular body from the inner ends 45 of the longitudinal end portions to a central portion of the cut which connects the two remaining ends of the transverse portions, projections disposed on opposite sides of the cut at each of the end portions thereof, and at 50 the central portion and means connecting the projections in pairs to contract the body.

2. A clamp connector, as claimed in claim 1, in which said tubular body comprises a straight member and the said projections at 55 each end are disposed at right angles to each other.

3. A clamp connector, as claimed in claim 1, in which said tubular body comprises a curved member and the said projections at 60 each end are disposed at right angles to each other.

In testimony whereof, I have signed my name to this specification this 29th day of May, 1925.

ABRAHAM BERNARD DIBNER.
